DEADLINE STABILIZER

Albert L. Stone, Palos Verdes Estates, Calif., assignor to Byron Jackson Co., Los Angeles, Calif., a corporation of Delaware

Application November 12, 1948, Serial No. 59,568

3 Claims. (Cl. 254—190)

This invention relates to the well drilling art. In the drilling of wells by the rotary method a drill string is suspended in a derrick by means of a cable or wire line which is reeved over a crown block on the top of the derrick and a travelling block which travels vertically within the derrick. One end of the drilling line is wound upon a spooling drum and the other end is fixed at a location near or below the derrick floor. That portion of the drilling line which extends from the fixed end to the crown block is known in the art as the "deadline."

It is the purpose of my invention to provide improved means for stabilizing this deadline against lateral vibration and whipping during drilling operations.

Whipping of the deadline may cause fouling of the line against the fingerboard or other parts of the derrick structure and thus damage the line by abrasion. Furthermore, continual whipping of the line may result in damage to individual strands of the line by fatigue at the point where the line enters the groove in the nonrotary or "dead" sheave of the crown block. Another undesirable consequence of whipping of the deadline is the adverse effect upon the weight indicator unit which conventionally is attached to the deadline to measure the tension therein in order to obtain a measure of the total weight supported by the travelling block. Vibration of the deadline causes fluctuation of the weight indicator pointer rendering it difficult to obtain a proper reading therefrom, and also causes excessive wear of the various moving parts of the weight indicator assembly.

It is essential that the stabilizer which is to be applied to the line to prevent whipping be mounted so that it can be accurately adjusted with respect to the position of the deadline. Since it is desirable that the deadline stabilizer be of universal application and be adapted to be used on various derrick installations, an adjustable mounting is of primary importance. Various types of crown blocks have the dead sheave located in various positions, and the hold-down devices used for anchoring the deadline are also of various designs and may be positioned in various locations relative to the derrick, depending upon the particular installation. The result is that the deadline may occupy slightly or widely differing positions within the derrick, depending upon the particular derrick, crown block and hold-down device.

It is therefore the principal object of this invention to provide a novel form of deadline stabilizer having novel adjustment means for positioning it in axial alignment with the deadline.

Another object is to provide an adjustable mounting for a deadline stabilizer which enables the stabilizer to be carried by the derrick and adjusted with respect to its inclination and position to avoid drag of the deadline due to stretch under varying load conditions.

Other objects and advantages will appear from a consideration of the following specification and illustrated in the drawings, wherein:

Figure 1 is a perspective view showing a preferred embodiment of my invention.

Figure 2 is a plan view thereof.

Figure 3 is a front elevation.

Figure 4 is a sectional elevation taken substantially on the lines 4—4 as shown in Figure 3.

Figure 5 is a plan view of a modified form.

Figure 6 is a side elevation thereof.

Figure 7 is a plan view of a further modification.

Figure 8 is a side elevation thereof.

2

Figure 9 is a front elevation showing adjustment in one plane.

Figure 10 is a front elevation showing adjustment in another plane.

In the drawings three embodiments of my invention are shown. In Figures 1 to 4 a universal ball and socket joint is adapted to be adjustably carried on the fingerboard and is arranged to support the deadline stabilizer device. The preliminary alignment is accomplished by bolting the assembly to the fingerboard in the approximate location required, and final alignment is obtained by manipulating the stabilizer unit about the universal joint. In the embodiment shown in Figures 5 and 6 a ball and socket universal joint is also provided, but a further endwise adjustment is provided by a novel form of mounting bracket. In Figures 7 to 10 the universal joint is not used and the stabilizer unit is adjustably carried on trunnions which extend in one direction and which are mounted for endwise movement in another direction on the same form of bracket assembly shown in Figures 5 and 6. In all embodiments mating joint fittings cooperate to provide adjustability between the stabilizer unit and the mounting assembly.

Considering in more detail the embodiments of this invention as shown in the drawings, complementary semi-cylindrical shell halves 10 and 11 are attached to a fingerboard mounting base 12 by means of a universal joint assembly generally designated 13. The complementary shell halves 10 and 11 are joined by a suitable hinge structure 14 near their upper and lower abutting edges and are provided with mating lugs 15 and 16 adjacent their other abutting edge. The lugs are connected by the pivoted bolt 17 and wing nut 18. The shell halves receive a resilient liner 19 which is preferably formed of natural or synthetic rubber or of resilient rubber-like composition. The resilient liner 19 is provided with an axial bore 20 normally of slightly larger diameter than the nominal size of the deadline cable 21. The liner 19 is split radially on one side as shown at 22 so that it may be slipped laterally into position on the deadline. Upon being so fitted to the deadline the resilient liner 19 is embraced within the shell halves 10 and 11 and the pivoted bolt 17 is tightened so that the shell halves squeeze the liner 19 and cause it to grip the deadline 21. The engagement of the deadline by the liner 19 is not severe enough to prevent axial movement of the deadline but is tight enough to apply an appreciable drag in the event of such movement. This drag serves to dampen out the whipping movement of the deadline.

The arm 23 is welded or otherwise secured to the shell portion 11 and carries a ball 24 on its outer end. The ball 24 is received within a two-part socket 25 defined by a housing 26 and a cap 27. Threaded elements 28 are tightened to clamp the cap 27 and housing 26 together to clamp the ball 24 in selected position. Lock washers may be provided for the threaded elements 28 if desired. The fingerboard mounting base 12 is preferably formed integral with the housing 26. Since the location of the deadline 12 and fingerboard 29 may vary materially with different arrangements of the derrick 30, several elongated slots 31 are provided in the mounting base 29. These slots 31 extend both longitudinally and transversely of the base 12 as shown. Bolts 32 extend through the slots to anchor the base 12 to the fingerboard 29. The axis of the stabilizer unit 33 may be approximately aligned with the path of the deadline by means of the bolts 32 which pass through the elongated slots 31, and the final angular adjustment is secured by manipulation of the universal joint 13.

A conventional safety line 34 may be attached to an eye 35 formed on the shell portion 10.

Referring to the modification shown in Figures 5 and 6, the stabilizer unit 33 may be substantially the same as that previously described and includes the same shell halves 10 and 11 enclosing the resilient liner 19. The ball 24 carried on the arm 23 is received within a socket, but the socket halves are formed by a base 50 having a cap 51 secured thereto by means of threaded elements 52. A socket 53 formed on the base 50 extends in a direction opposite to that of the arm 23 and is adapted to receive one end of a threaded bar 54 or carrier. The bar 54 is

secured to the base 50 by any convenient means such as, for example, by welding. This bar extends through a cylindrical tube 55 on the support assembly generally designated 56. The support assembly 56 comprises a plate 57 to which is centrally welded the cylindrical tube 55 and the clamping supports 58 which serve to secure the plate relative to a portion 59 of the derrick assembly 30. The clamps 58 may comprise a continuous bar having its ends threaded and extending through apertures formed in the plate 57. Retaining nuts 60 hold the clamps 58 in assembled relationship.

The diameter of the tube 55 is slightly larger than that of the threaded bar 54 enabling the latter to be moved axially through the tube. Clamping nuts 61 are provided on the threaded bar 54 to secure the bar in adjusted position with respect to the support assembly 56. It will be noted in Figure 6 that the center of the ball and socket joint 13 is laterally offset from the axis of the threaded bar 54. This lateral offset permits the base 50 to be swung at any desired angular position to secure lateral adjustment of the position of the stabilizer unit 33.

In that form of my invention shown in Figures 7 to 10, the same form of resilient insert 19 may be employed, but the enclosing shell may take a somewhat different form. The shell half 80 is bolted to the shell half 81 by means of the bolts 82. Rearwardly extending arms 83 on the shell portion 81 provide bearings for the laterally extending trunnions 84 formed on the forward end of the carrier or threaded bar 85. Bearing caps 86 cooperate with the arms 83 to secure the arms to the trunnions. In effect the trunnions are clamped between the bearing caps 86 and the arms 83 by means of the bolts 87. The supporting clamp assembly 88 may be substantially identical to that described in connection with the previous embodiment. Figure 9 shows how the stabilizer unit generally designated 89 may be tilted about the axis of the threaded bar 85, and Figure 10 shows how the angular adjustment in a plane at right angles thereto may be accomplished. The adjustment as shown in Figure 10 may be made by loosening the clamping bolts 87 to permit the stabilizer unit 89 to move about the axis of the trunnions 84.

It will be understood from the above descriptions that each of the three embodiments provides a universal mounting for a deadline stabilizer such that the position of the bore in the liner 19 may be moved both laterally and transversely, and in addition the bore may be inclined at any desired angle within the limits imposed by the particular construction employed.

Having fully described my invention, it is to be understood that I do not wish to be limited to the details herein set forth, but my invention is of the full scope of the appended claims.

I claim:

1. A cable stabilizer for dampening the lateral vibration and whipping of a cable of a rotary oil well drilling derrick, comprising in combination: a pair of nonresilient members defining a shell, a liner of resilient material having at least a portion of its outer boundary confined within the shell and having a central opening extending therethrough to receive a cable, said shell and said liner forming a stabilizer unit, a carrier having a longitudinal axis and having a first joint fitting, a second joint fitting formed integrally with one of said nonresilient members and mating with said first joint fitting to mount said unit on said carrier for pivotal movement about a point spaced from said central opening and laterally offset from the longitudinal axis of said carrier, said first joint fitting and said second joint fitting being adjustably interengaged to permit pressure to be applied to one of said fittings by the other fitting to retain said unit in an adjusted position, a

mounting member including means to secure said member to an element of a derrick structure, and adjustable connecting means supporting said carrier on said member to provide adjustment of said unit with respect to said derrick element.

5 2. A cable stabilizer for dampening the lateral vibration and whipping of a cable of a rotary oil well drilling derrick, comprising in combination: a pair of nonresilient members defining a shell, a liner of resilient material having at least a portion of its outer boundary confined within the shell and having a central opening extending therethrough to receive a cable, the liner having a slot extending from the central opening to the outer boundary of the liner to permit the liner to be applied laterally to a cable, said shell and said liner forming a stabilizer unit, a carrier having a longitudinal axis and having a base and a cap for said base, said base and cap comprising a ball socket offset laterally from the longitudinal axis of said carrier, a ball within said socket and formed integrally with one of said nonresilient members, said ball and socket pivotally mounting said unit on said carrier for universal pivotal movement, said base and cap being adjustably interengaged to apply pressure to said ball to retain said unit in an adjusted position, a mounting member including means to secure said member to an element of a derrick structure, and adjustable connection means supporting said carrier on said member to provide adjustment of said unit with respect to said derrick element.

3. A cable stabilizer for dampening the lateral vibration and whipping of a cable of a rotary oil well drilling derrick, comprising in combination: a pair of nonresilient members defining a shell, a liner of resilient material having at least a portion of its outer boundary confined within the shell and having a central opening extending therethrough to receive a cable, said shell and said liner forming a stabilizer unit, a carrier having a longitudinal axis and having a first pair of joint fittings, a second pair of joint fittings formed integrally with one of said nonresilient members and mating with said first pair of joint fittings to mount said unit on said carrier for pivotal movement about an axis spaced from said central opening and substantially perpendicular to said longitudinal axis, said first pair of fittings and said second pair of fittings being adjustably interengaged to permit pressure to be applied to one of said pairs of fittings by at least one of the other pair of fittings to retain said unit in an adjusted position, a mounting member including means to secure said member to an element of a derrick structure, and adjustable connecting means supporting said carrier on said member to provide adjustment of said unit with respect to said derrick element, said unit being capable of universal pivotal movement with respect to said derrick element.
